[57] CLAIM

The ornamental design for a seat or similar article, as shown and described.

DESCRIPTION

FIG. 1 is a front perspective view of a seat showing our design in the form of a sofa.
FIG. 2 is a side perspective view of the design of FIG.
1 shown in the form of a chair; and
FIG. 3 is a side-rear perspective view of the design shown in FIG. 1 in the form of a love seat.
